CLAIM

The ornamental design for a cover for electronic device, as shown and described.

DESCRIPTION

FIG. 1 is a perspective view of front, bottom and right side of a cover for electronic device showing my new design; FIG. 2 is a perspective view of front, bottom and left side thereof;

FIG. 3 is a perspective view of rear, top and left side thereof; FIG. 4 is a perspective view of rear, bottom and left side thereof;

FIG. 5 is a front view thereof;

FIG. 6 is a rear view thereof;

FIG. 7 is a left side view thereof;

FIG. 8 is a right side view thereof;

FIG. 9 is a top view thereof;

FIG. 10 is a bottom view thereof; and,

FIG. 11 is a perspective view showing the claimed design in its environment of use.

The broken lines in FIGS. 3, 4, and 6-10 depict portions of the cover for electronic device that form no part of the claim. The broken lines in FIG. 11 illustrate environmental structure and form no part of the claimed design.

1 Claim, 7 Drawing Sheets
